DESIGN FOR A SHOE

Anthony A. Ryan, Spencer, Mass., assignor to Kleven Shoe Co., Spencer, Mass., a corporation of Massachusetts

Application November 10, 1934, Serial No. 53,970

Term of patent 3½ years

To all whom it may concern:

Be it known that I, Anthony A. Ryan, a citizen of the United States, residing at 55 Cherry Street, Spencer, in the county of Worcester, and Commonwealth of Massachusetts, have invented a new, original, and ornamental Design for a Shoe, of which the following is a specification, reference being had to the accompanying drawing, forming a part thereof, in which

Fig. 1 is a view in side elevation of a shoe showing my design; and

Fig. 2 is a plan view of the shoe, the outline of the shoe being conventional and shown in dotted lines in both figures.

I claim:

The ornamental design for a shoe substantially as shown and described.

In testimony whereof, I have affixed my signature hereto.

ANTHONY A. RYAN.
